UNITED STATES PATENT OFFICE.

JOHN P. ENGEL, OF BROOKLYN, NEW YORK.

PASSENGER CONVEYANCE.

Application filed April 9, 1920, Serial No. 372,468. Renewed September 6, 1922. Serial No. 586,538.

To all whom it may concern:

Be it known that I, JOHN P. ENGEL, a citizen of the United States, residing at Brooklyn, in the county of Kings and State 5 of New York, have invented new and useful Improvements in Passenger Conveyances, of which the following is a specification.

This invention relates to passenger conveyances.

Some of the objects of the invention are: to equip a passenger conveyance with an apparatus which will permit its being operated successfully by one man; to equip a passenger conveyance with an apparatus so that passengers may be taken on and are permitted to get off without crowding and the obviation of congestion; to provide an apparatus for a passenger conveyance which 20 permits passengers to enter the conveyance at the front end and permits of their exit at the rear end and prevents their entrance through the exit, the said apparatus embodying among other things a visual signal 25 and a movable step, which step is actuated by a passenger to operate the signal for the starting of the conveyance.

With these and other objects in view the invention resides in the arrangement and 30 combination of elements hereinafter more fully described and illustrated in the accompanying drawings, in which:—

Figure 1 is a sectional diagrammatic view illustrating certain features of the present 35 invention.

Figure 2 is an enlarged fragmentary view at one of the exists of the passenger compartment.

Figure 3 is an enlarged vertical view of 40 one of the turnstiles forming a part of the apparatus which is arranged adjacent the exit.

Figure 4 is a perspective view illustrating one of the steps and its correlated parts.

Figure 5 is a detail sectional view taken 45 on the line 5—5 of Figure 2.

Figure 6 is a detail view of parts of the step raising and lowering mechanism.

As stated, the present invention contemplates the equipping of a passenger conveyance with an apparatus permitting the conveyance to be operated successfully by one man. The passenger compartment, in accordance with this invention is to be provided with a plurality of entrances and a 50 plurality of exits. An entrance and an exit

are arranged at each side of the compartment with the entrance at the front end of the compartment and the exit occurring at the rear end thereof. The apparatus for controlling the entrance and the exits is such as to permit the conveyance to be operated from either end and the apparatus embodies two identical mechanisms. For the sake of convenience the following explanation will be 60 limited to but a single mechanism complete in itself for controlling the entrance and exit of passengers when the car is traveling in a particular direction.

Referring now to the drawing, it will be 70 seen that the conveyance will include a passenger compartment 10 having at each side an entrance 11 and an exit 12. The exit 12 is normally closed by a door 13 which moves on a vertical pivot 14. Arranged 75 with respect to the door 13 is a step 15 arranged for movement on stub shafts 15^a to a raised and lowered position. The step being in a raised position when the door 13 is closed and is adapted to be disposed in 80 its lowered position when the door 13 is in an open position. The turnstile 16 is arranged in proximity to the exit 12. The turnstile comprises sets of radially extending obstructing pivoted arms which are arranged in superposed groups. The turnstile 85 may be rotated in one direction only so as to permit the exit to passengers but prevents entrance at the exit 12.

In order to permit of the exit of passengers at the exit 12, the door 13 is opened outwardly and the step 15 is lowered simultaneously with the opening of the door 13 and such action is accomplished by the devices presently described. A vertically disposed shaft 17 mounted in suitable bearings has secured to the upper end thereof an operating handle 18 and the lower end of said shaft is provided with a pinion 19. The pinion 19 meshes with teeth 20 of a 90 rod 21 which extends lengthwise of the compartment 10 at the underside thereof. The teeth 20 of the rod 21 are held in mesh with the teeth of the pinion 19 by the employment of an idler pinion 22 which meshes 95 with teeth 23 of the rod 21. It is to be understood that any other suitable means in lieu of the pinion 22 and the teeth 23 may be used to prevent the displacement of the rod 21. The rod 21 is provided with teeth 100 24 which mesh with a pinion 25 which meshes with a pinion 26 at the lower end 110

of the door pivot 14. An idler pinion 27 which meshes with teeth 28 of the rod 21 is employed for maintaining an operative relation between the teeth 24 and the teeth 5 of the pinion 25. The free end of the rod 21 has connection with an arm 29 by the employment of a ball and socket joint 30, and this arm 29 is connected to a bar 31 in a manner so as to have movement with respect thereto. The step 15 is provided with arms 32 which have their free ends in securement with the bar 31. It will now be manifest upon proper manipulation of the handle 18, the rod 21 will be moved and through 10 intervention of the pinions 25 and 26, the door 13 will be made to swing outwardly to an open position and, at the same time the step 15 will be lowered, due to the fact that the arm 29 will be moved along the bar 15 31 until the part surrounding the bar 31 encounters the upper end of the arm 32 adjacent the weighted arm. Further movement of the rod 21 causes further movement of the arm 29 which can be upwardly only, 20 such movement being permitted by reason of the ball and socket joint 30, and the loose connection of the end of the arm 29 to the bar 31. In moving the rod 21 in an opposite direction to that just explained, 25 the door will be swung to a closed position and the step 15 will be raised, due to the fact that the end of the arm surrounding the bar 31 will move along it until it encounters the pin 34 secured to the bar 31. This latter action is supplemented by weights 35. 30 The turnstile 16, as stated, may be rotated in one direction only and embodies upper and lower groups of arms 36. The upper groups of arms 36 have pin and slot connection 37 with vertically disposed bars 38 supported by an upper member 39 and an intermediate member 40 secured to a central shaft 41 mounted in supports 42. The lower groups of arms 36 have pin and 40 slot connection 43 with vertically disposed bars 44 supported by the member 40 and a lower member 45. The inner ends of the upper groups of arms 36 have pivotal connection with movable bars 46. The bars 46 move in guide openings in the members 39 and 40. The upper end of each of the bars 46 is provided with a roller 47 each of which is held in contacting relation with a cam surface 48 by a compression spring 49 45 interposed between a pin 50 secured to the shaft 41 and the member 39. The inner ends of the lower groups of arms 36 are pivoted to movable bars 51. The bars 51 move in guide openings in the members 40 50 at 45 and the lower end of each bar 51 is provided with a roller 52. Each roller 52 is held in contacting relation with a cam surface 53 by a spring 56 interposed between a pin 57 secured to the bar 51 and the member 45. It will now be manifest that in

moving the arms 36 in a clockwise direction they will be made to move in a collapsed condition, immediately they have passed the exit opening. The upper groups of arms 36 will be moved downwardly in an inclined position and the lower groups of arms 36 will be moved upwardly to an inclined position. The object of collapsing the arms 36 is to give more space in the compartment 10 and at the same time, under 70 the present arrangement, the ceiling of the compartment 10 will not interfere with the collapsing of the arms, the uppermost of which are in close proximity thereto. The cam surfaces 48 and 53 are such as to move 75 the arms 36 to obstructing positions immediately before they arrive at the exit opening. A gravity pawl 58 and a ratchet 59 prevent the turnstile from rotating in a counter-clockwise direction. 80

In order that the operator of the conveyance may be apprised of the exit of the passenger or passengers at a particular point to start the conveyance a visual signal is employed. This signal consists of an 90 electric lamp arranged in a circuit having a suitable source of electrical energy and a circuit closer which is arranged upon the wing 33 and is actuated by the step 15. When the step 15 is arranged in a lowered 95 position, a slight shifting of the arm 29 by the manipulation of the operating handle 18 permits a slight upward movement of the step 15, so that as the weight of the passenger is removed from the step 15 the 100 weights 35 will cause the step 15 to actuate the circuit closer 61 to thus light the lamp 60. When the lamp 60 remains lighted for what will be an unusual length of time, this will be the signal to start the conveyance. 105

While there has been shown the preferred embodiment of my invention, it is to be understood that the right is reserved to make any and all necessary changes, alterations and modifications within the scope of the 110 claims hereunto appended.

What is claimed as new is:—

1. A passenger conveyance as characterized, including a passenger compartment having entrances and exits, in combination with an apparatus including a correlated door and movable step at each exit, means for actuating said doors and steps simultaneously for permitting the entrance of passengers to the compartment and their exit 115 therefrom through said exits but preventing their entrance through said exits, and visual signal means, actuated upon the upward movement of said steps.

2. A passenger conveyance as characterized, including a passenger compartment having entrances and exits, in combination with an apparatus including a correlated door and movable step at each exit, means for opening the doors and for lowering the 120 125 130

- steps simultaneously for permitting the entrance of passengers to the compartment and their exit therefrom through said exits but preventing their entrance through said exits, 5 and visual signal means, actuated by either of said steps upon their upward movement.
3. A passenger conveyance as characterized, including a passenger compartment having an entrance and an exit, a turnstile arranged adjacent the exit, a door normally closing said exit, a step arranged at said exit in relation to said door, and means operative for effecting the opening of the door and the lowering of the step to permit exit of passengers.
- 10 4. A passenger conveyance as characterized, including a passenger compartment having an entrance and an exit, a turnstile embodying groups of arms, means for effecting the movement of certain groups of said arms to obstructing and non-obstructing 20 positions, said turnstile arranged adjacent the exit, a door normally closing said exit, a step arranged at said exit in relation to said door, and means for effecting the opening of the door and the 25 lowering of the step, to permit exit of passengers.
- 25 5. A passenger conveyance as characterized, including a passenger compartment having an entrance and an exit, a turnstile rotatable in one direction only arranged adjacent the exit, a door normally closing said exit, a step arranged at said exit in relation to said door, and means for effecting the opening of the door and the 30 lowering of the step to permit exit of passengers.
- 35 6. A passenger conveyance as characterized, including a passenger compartment having an entrance and an exit, a turnstile embodying groups of radially obstructing pivoted arms, means for effecting the upward movement of certain groups of arms and the downward movement of certain groups of arms to obstructing and non-obstructing 40 positions, said turnstile arranged adjacent the exit, a door normally closing said exit, a step arranged at said exit in relation to said door, and means for effecting the opening of the door and the 45 lowering of the step, to permit exit of passengers.

In testimony whereof I have affixed my signature.

JOHN P. ENGEL.
